GAS BURNER

Delmond L. Getz and Robert O. Hedges, Springfield, Ohio, assignors, by mesne assignments, to Kelsey-Hayes Wheel Company, Detroit, Mich., a corporation of Delaware

Application October 23, 1950, Serial No. 191,594

2 Claims. (Cl. 158—110)

This invention relates to gas burners, and more particularly to gas burners for conversion use in installations such as furnaces and boilers.

One of the principal objects of the invention is to provide a gas conversion burner which is simple and economical to construct and install, which will operate effectively and efficiently as a conversion burner in a furnace or boiler originally designed for coal firing, and particularly to provide such a gas burner which will operate with minimum noise of the type usually associated either with the mixing of the gas and primary air or with control of the flame pattern.

It is accordingly another object of the invention to provide a gas conversion burner having a combustion head of such construction and operating characteristics as to provide a fan-shaped flame without requiring the use of refractory hearths or spreader baffles of ceramic or metallic construction in the path of the flame which commonly contribute to flame noise and rumble as a result of the impingement of the flame thereon.

These characteristics are obtained in accordance with the invention by means of a combustion head which effects sandwiching of the initial mixture of gas and primary air between two layers of secondary air as the mixture is discharged from the combustion head. This effect is obtained by discharging the primary air in a generally flat annular spray to give a circular fan-like flame pattern, with the secondary air being discharged in similar flat sprays immediately adjacent both sides of the mixed spray, and the secondary air sprays act to spread the flame toward the side walls of the furnace or boiler to give the desired fan-shaped flame without the use of refractory hearths or spreader baffles.

It is accordingly an object of the invention to provide a combustion head for a gas conversion burner having a plurality of discharge orifices or slots arranged circumferentially thereof for discharge around substantially the entire circumference of the combustion head and adapted to be supplied with gas and air in such manner as to discharge a mixture of gas and primary air through the central slot and to discharge secondary air through the outer slots on either side of the gas and primary air mixture in fan-shaped pattern.

It is also an object of the invention to provide a gas conversion burner having a primary air damper and venturi tube combination for admitting gas and primary air to the combustion head which is so constructed as to produce a gradually changing air opening of maximum cross-section for a given area for admitting the primary air in all settings thereof and thus to accomplish initial mixing of the gas and primary air with minimum noise.

Other objects of the invention will be apparent from the following description, the accompanying drawings and the appended claims.

In the drawings:

Fig. 1 is a view in vertical section showing a gas conversion burner in accordance with the invention, the view being generally in section on the line 1—1 of Fig. 2;

2

Fig. 2 is a view of the burner taken partly in plan and partly in section on the line 2—2 of Fig. 1, with additional portions of the casing broken away to illustrate details of internal construction;

5 Fig. 3 is a rear view of the burner with the casing broken away;

Fig. 4 is an enlarged fragmentary view of the secondary air damper adjusting mechanism;

Fig. 5 is a fragmentary section on the line 5—5 of

10 Fig. 4;

Fig. 6 is an enlarged fragmentary section on the line 6—6 of Fig. 7 showing the primary air damper and venturi tube;

Fig. 7 is a section on the line 7—7 of Fig. 6;

Fig. 8 is an enlarged sectional view through the combustion head;

Fig. 9 is a fragmentary view in perspective showing one of the lugs on the inner casing of the mixing chamber for receiving locking clips on the mixing casing cover;

20 Fig. 10 is a detail view in perspective showing one of the locking clips on the mixing casing cover;

Fig. 11 is a fragmentary view in perspective showing one of the lugs for supporting the outer casing of the mixing chamber on the wind box; and

Fig. 12 is a diagrammatic view illustrating the operation of the combustion head.

Referring to the drawings, which illustrate a preferred embodiment of the invention, the control housing

30 13 is provided with a cover 14 hinged thereto at 15 and having handle knobs 16. The ends 17 of the control cabinet are provided with louvers 18 for admitting air to the interior of the cabinet for transmission through the slide 20 to the secondary air wind box 21 in which is mounted the combustion head indicated generally at 22. The wind box 21 includes a bottom plate 24, a top plate 25 and a wrapper 26 around the end thereof, and the connection between the wind box and slide is axially adjustable to fit different installation conditions. Legs 40 27 are adjustably mounted at 28 in the control cabinet and wind box for properly positioning the combustion head with respect to the original grate line of the furnace or boiler.

The cabinet 13 is provided with an enlarged opening 30 for admitting secondary air to the slide and wind box, and this opening is controlled by an adjustable secondary air damper 31 hinged to the cabinet by means of brackets or tabs 32. A curved adjusting guide 33 of sheet metal for the damper 31 is welded or otherwise secured at 34 to the bottom of the slide 20 and is provided with an arcuate slot 35. The guide 33 passes through a slot 36 in damper 31, and a bracket 37 on the damper has a nut 38 welded thereto to receive a lock screw 40 for releasably securing the damper in fixed relation with guide 33 to hold it in adjusted position in accordance with the desired effective opening for secondary air.

65 The gas pipe 44 for connection to the main supply line leads to the control manifold comprising gas valve 45 and pressure regulator 46, the gas valve being operated by the room thermostat or by the pilotstat 47 and safety pilot 50 in the usual way. The pilot 50 is shown as mounted in the wind box 21 by means of a bracket 51 and is provided with a supply tube 52 and vent tubes 53 supported in the control cabinet by a bracket 55.

From the control manifold, the gas passes through the gas manifold 59 to the gas spud 60, which is shown in detail in Figs. 6 and 7 and is supported within the slide 20 by a bracket 61 having a generally U-shape in side elevation. The spud 60 is provided with a large bore 62 at its entering end which narrows at 63 to a discharge orifice 65 of restricted dimensions. The spud cooperates with the belled end 66 of a tube 70 to form a venturi

combination for mixing primary air with the gas. The tube 70 includes a cylindrical portion 71 slideable for adjustment within the primary air tube 72 leading to the combustion head 22, and a clamp 73 is brazed to tube 70 for attachment to the spud bracket 61 to maintain the belled end 66 in fixed relation with the discharge end of the spud defining an unobstructed inlet passage 75 for primary air to the tube 70.

The admission of primary air to this venturi arrangement is controlled by a conical damper 77 having a hub portion 78 slideable on the gas spud 60. A bracket 79 is secured to the hub 78 and is slotted at its upper end for connection to an adjusting screw 80 threaded in the upper end portion of the spud bracket 61. A control rod 81 is secured to the rearward end of the screw 80 and extends into the interior of the control cabinet, where it is supported in bearing 82 having a lock screw 83. A control knob 85 provides for convenient rotation of rod 81 when the lock screw 83 is released.

In operation, the gas transmitted under pressure to the spud 60 is discharged at high velocity through the restricted orifice 65 into the tube 70. The velocity of the gas passing into this tube draws primary air into the tube 70 through the inlet passage 75 for mixture with the gas inside tube 70 and transmission to the combustion head. The amount of primary air drawn into the venturi tube 70 is readily regulated by changing the position of the damper 77 on the gas spud as described, and it will be seen that at all settings of the damper, there is provided an unobstructed air inlet passage of gradually changing effective flow area which has been found to effect the desired admission and mixing of air with the gas with minimum noise.

The structure and operation of the combustion head 22 is shown in detail in Figs. 8 to 12. The annular mixing chamber 90 for the gas and primary air is defined by an outer casing 91 and an inner casing 92, the outer casing 91 being adapted at 93 for direct connection with the air tube 72. The casing 91 is supported on an upstanding collar portion 95 on the top 25 of the wind box and defines therewith an annular chamber 96 for receiving secondary air from the inside of the wind box.

The casing 91 has the peripheral lip portion 99 at its upper end supported in spaced relation with the upper end of the collar 95 to define therewith a substantially continuous annular discharge orifice or slot 100 from the chamber 96 extending circumferentially about the combustion head. Referring to Figs. 8 and 11, the lip portion 99 on casing 91 is provided with a plurality of lugs 101 on the underside thereof, and these lugs are cut out at 102 to fit the upper end of the collar 95, thus defining the slot 100 between the underside of lip 99 and the upper rim of collar 95. At its lower end, the casing 91 includes a cross bar 105 secured by a bolt and nut 106 to a bracket 107 welded or otherwise secured to the bottom 24 of the wind box.

The inner casing 92 of the mixing chamber also includes a circumferential lip 109 which is supported in spaced relation with the lip 99 to form a circumferential discharge orifice or slot 110 for the mixed gas and primary air from the mixing chamber 90. The casing 92 is generally of inverted bell-shape, with its lower end 111 being fitted within the cylindrical boss portion 112 at the lower part of casing 91. On the upper surface of the lip portion 99 of casing 91 are a plurality of upstanding lugs 113 which engage the underside of the lip 109 and thus maintain it in desired spaced relation above the lip 99 to define therewith the discharge slot 110. Thus with the lip 99 flared upwardly as shown and terminating in a flat land 114, the mixed gas and air from chamber 90 is discharged through slot 110 in a substantially flat annular spray arranged in a fan-like pattern circumferentially of the combustion head.

The casing 92 forms a central chamber 115 for receiving secondary air from the wind box, and it is provided with a top cover 119 supported in such manner as to define

with the lip 109 a substantially continuous annular discharge orifice or slot 120 for the secondary air from the chamber 115. The lip 109 is provided with a plurality of upstanding lugs 121 on its periphery which have tapered upper surfaces 122 for receiving the downwardly sloping rim portion of the cover 119 to support the cover in the desired spaced relation with lip 109 to define the slot 120.

In order to secure the cover 119 removably on casing 92, each of the lugs 121 is provided with a slot 123 on its inner side for locking engagement with one of the locking clips 125 on the cover 119. As shown in Fig. 10, the clip 125 is generally Z-shaped and includes a lower flange which has an upwardly sloping portion 126 and a flat portion 127 terminating in an upstanding tab 128. Thus when the cover 119 is set on the casing 92 and rotated in clockwise direction as viewed from above, the flange portion 126 on each clip will slide into slot 123 on one of the lugs 121 until it frictionally engages the overhanging portion of this slot to lock the slot in place, the rotation of the cover being limited by engagement of the tabs 128 with the sides of the lugs 121.

In operation, the mixture of gas and primary air ignited by the pilot 50 is discharged from the slot 100 in a substantially flat fan-shaped flame around the entire circumference of the combustion head. At the same time, the air is drawn through damper opening 30 by natural draft action into slide 20, and while some of this air is sucked into venturi tube 70 as primary air, the remainder flows into the chambers 96 and 115 and is discharged through the slots 100 and 120 as initially flat annular sprays immediately below and above the flame which intermix with the flame to provide the proper amount of air for complete combustion. In addition, the action of these two air rings together with the velocity discharge of the gas flame from the intermediate slot 110 produces the desired overall fan-shaped pattern for the flame and causes it to spread to the side walls of the furnace or boiler without the aid of refractory hearths, spreader baffles or other flame directing members.

It will also be seen that this burner construction is easily adaptable to varied installation conditions without altering its operating characteristics. The sliding connection between the slide 20 and the wind box make it possible to vary the position of the control cabinet as required for a particular installation, and the adjustable legs are similarly of assistance in fitting the burner in proper relation with a particular furnace or boiler. Also, with the gas spud 60 and venturi tube 70 mounted in the desired fixed relation by means of the common mounting bracket 61 and with the other end of the venturi tube slideable in the air tube 72, a similarly adjustable connection is provided without affecting the proper operating relationship of the spud and the belled end portion of the venturi tube.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A gas burner combustion head for delivering a substantially flat fan-shaped flame establishing evenly distributed heating of a combustion chamber free of external flame spreading means, comprising a secondary air wind box, a pair of inner and outer annular casings arranged in telescoped relation to form a central chamber and a surrounding annular chamber, means supporting said casings in substantially vertical position partially within and extending above said wind box, means within said wind box for connecting said annular chamber to a source of mixed gas and primary air, circumferential lips on said casings projecting substantially radially therfrom in vertically spaced relation over a substantial distance beyond said outer casing and of substantially the same diameter and forming a corresponding circumferential discharge passage of substantial radial extent from said annular chamber to

cause said gas-air mixture to be discharged in a flat fan-shaped pattern, a cover plate for said inner casing supported in vertically spaced relation with said inner casing lip, said cover being of substantially the same diameter as said inner casing lip to define therewith a circumferential discharge slot for discharging secondary air radially from said central chamber above said discharging gas-air mixture to maintain said discharging gas-air mixture in said flat fan-shaped pattern, a collar on the top of said wind box including a tubular portion surrounding and of greater diameter than said outer casing and of lesser diameter than said lip on said outer casing to form with said outer casing a further annular chamber for secondary air, means maintaining said outer casing lip and the upper periphery of said collar in vertically spaced relation to form an additional circumferential slot for substantially radial discharge of secondary air below said discharging gas-air mixture, and means separately connecting the interiors of said collar and said inner casing with the interior of said wind box to supply secondary air thereto for discharge through said air discharge slots.

2. A gas burner combustion head for delivering a substantially flat fan-shaped flame establishing evenly distributed heating of a combustion chamber free of external flame spreading means, comprising a secondary air wind box, a generally cup-shaped main casing having a tubular opening in the bottom thereof, means supporting said main casing with the lower end thereof within said wind box, an inner casing having the lower end thereof mounted in said tubular opening and extending vertically within said main casing to define therewith a central chamber and an annular chamber, means for supplying a mixture of gas and primary air to said annular chamber, circumferential lips of substantially the same diameter projecting radially from both of said casings in vertically spaced and overlying relation to form a discharge slot from said annular

chamber of correspondingly substantial radial extent causing said gas-air mixture to be discharged therefrom in a flat fan-shaped pattern, said inner casing being open at the lower end thereof to receive secondary air from said wind box, a cover on the upper end of said inner casing supported in vertically spaced relation with said lip on said inner casing to define therewith a circumferential discharge slot for said secondary air, said cover being of substantially the same diameter as said lips to cause said secondary air to be discharged radially above said discharging gas-air mixture to maintain said discharging mixture in said flat fan-shaped pattern, a tubular collar of greater diameter than said main casing extending upwardly from the top of said wind box and opening at the lower end thereof into said wind box to receive secondary air directly therefrom, said collar being of lesser diameter than said lip on said main casing, and means maintaining said lip and the top of said collar in vertically spaced relation to form an additional circumferential discharge slot for primarily radial discharge of secondary air below said discharging gas-air mixture.
